UNITED STATES PATENT OFFICE

ETTA S. MARTIN, OF CHICAGO, ILLINOIS, ASSIGNOR, BY MESNE ASSIGNMENTS, TO BENSEL AND MARTIN, OF EAST ORANGE, NEW JERSEY, A FIRM COMPOSED OF ARLINGTON BENSEL AND CHARLES W. MARTIN

SAFETY RAZOR

Application filed July 8, 1932. Serial No. 621,396.

This invention appertains to safety razors, and more particularly to safety razors of the type embodying dual, superimposed shaving blades, such as is illustrated in my pending application, Serial Number 617,285, filed June 15, 1932.

One of the primary objects of my invention is to provide new and novel means for spacing the blades, so that the desired curvature will be imparted to the blades to give the desired smooth, close shave, and to permit the effective cleaning of the razor and blades by merely agitating the razor in a bowl of water.

Another prime object of my invention is to provide a safety razor embodying a pair of dual shaving blades, with novel spacing members in the form of U-shaped leaf springs, one of the legs of the spring members being of a corrugated or sinuous form, so as to insure the proper spacing of the blades, and to insure the passage of water between the blades during the cleaning operation, the U-shaped spacing members acting to hold one of the blades in position during the assembling of the razors.

A further object of my invention is the provision of novel means for associating the U-shaped spring spacing members with the razor, whereby the same will be accurately held in position against accidental displacement, so as to insure the proper association thereof with the blades.

A still further object of my invention is to provide novel spacing members of the above character, which can be manufactured at an extremely low cost and quickly associated with the razor and blades.

With these and other objects in view, the invention consists in the novel construction, arrangement and formation of parts, as will be hereinafter more specifically described, claimed and illustrated in the accompanying drawing, in which drawing:

Figure 1 is a transverse section through a safety razor embodying the novel features of my invention.

Figure 2 is a longitudinal section through the razor taken on the line 2—2 of Figure 1.

Figure 3 is a fragmentary transverse sec-

tion illustrating a slightly modified form for holding one of the spacing members in position.

Figure 4 is a view similar to Figure 3, illustrating a further modified form for holding a spacing member in position.

Figure 5 is a side elevation illustrating another form of spacing member.

Referring to the drawing in detail, where-in similar reference characters designate corresponding parts throughout the several views, the letter A indicates a safety razor, which comprises a guard 10 and a clamping plate 11, between which the dual shaving blades 12 and 13 are adapted to be positioned. The guard 10 and the clamping plate 11 are adjustable toward and away from each other in any preferred manner, and, as shown, the clamping plate 11 can be provided with a threaded stud 14 which is adapted to extend through the blades 12 and 13, and the guard 10, and into a threaded socket formed in the inner end of the manipulating handle 15.

The guard 10, or the clamping plate 11, can likewise be provided with any desired type of means for holding the blades in position against swinging movement while the razor is in use.

In accordance with my present invention I provide novel means for holding the cutting blades 12 and 13 in their proper spaced position, and this means insures the proper curvature to the blades so as to bring about the correct shaving operation. This novel spacing means for the blades embodies substantially U-shaped, resilient, spacing members 16, which are adapted to be disposed on the opposite sides of the razor. Each of the spacing members 16 embodies spaced inner and outer legs 17 and 18 and a connecting resilient bite portion 19. In accordance with my invention the inner leg 17 can be corrugated or formed in a sinuous manner, so as to provide in effect lugs 20 with channels 21 therebetween.

In the use of these spacing members 16, the same are preferably slipped over the guard 10 and over one blade 12 directly inwardly of the teeth of the guard. The other leg 18 can engage the outer face of the guard, and owing to the resilient connection between the legs 300

17 and 18, the leg 17 tends to hold the blade 12 in position.

After the spacing members have been properly disposed, the clamping plate 11 and the other blade 13 can be arranged in place, after which the handle 15 can be manipulated so that the blades will be held in their properly spaced position with the desired curvature.

While I have stated that the spacing members are associated with the guard 10, it is to be understood that the same can be associated with the clamping plate 11, in which the instance the same will initially engage the blade 13.

15 It is essential that the spacing members be properly and accurately disposed so that the same will be positioned inwardly of the cutting edges of the blades, and I provide means for insuring this proper positioning of said members.

As shown in Figure 1 of the drawing, the outer face of the guard 10 can be provided with longitudinal grooves 22, in which the outer legs 18 of the spacing members can fit.

25 This form of my invention is open to modification, and in Figures 3 and 4 I have shown two other forms of this feature of the invention. In Figure 3 I have shown eyes 23 for receiving the lower leg, and in this instance the lower leg can be of a circular shape in cross section.

In Figure 4 I have shown the guard provided with openings 24 extending longitudinally through the same, into which the outer legs can fit. In this form of the invention the legs 18 are entirely hidden from view.

While I have stated that the inner leg 17 is of a corrugated or sinuous form, obviously the leg can be formed flat and provided with oppositely directed lugs or pins 25 to form the desired spacing members and channels.

The U-shaped spring spacing members can be manufactured at a low cost and serve as an admirable means for properly spacing the blades and to insure the easy cleaning of the blades by the forming of passage-ways or channels between the blades.

Changes in details may be made without departing from the spirit or scope of the invention, but what I claim as new is:

I claim:—

1. A safety razor comprising a guard, a clamping plate, means for adjusting the guard and clamping plate toward and away from each other, a pair of super-imposed blades arranged and clamped between the guard and plate, and U-shaped spacing mem-

bers disposed on opposite sides of the longitudinal center of the razor and extending parallel with the longitudinal edges of the blades with one leg of each member disposed between the blades, said members gripping one of said blades.

2. A safety razor comprising a guard, a clamping plate, means for adjusting the guard and clamping plate toward and away from each other, a pair of super-imposed blades arranged and clamped between the guard and plate, and means for spacing the blades including a substantially U-shaped resilient member having inner and outer legs, one of said legs being disposed between the blades inwardly of the cutting edges thereof.

3. A safety razor comprising a guard, a clamping plate, means for adjusting the guard and clamping plate toward and away from each other, a pair of super-imposed blades arranged and clamped between the guard and plate, means for spacing the blades including a substantially U-shaped resilient member having inner and outer legs, one of said legs being disposed between the blades inwardly of the cutting edges thereof, and means on the inner leg for engaging the opposite faces of the blades and forming water channels therebetween.

4. A safety razor comprising a guard, a clamping plate, means for adjusting the guard and clamping plate toward and away from each other, a pair of super-imposed blades arranged and clamped between said guard and plate, and means for spacing the blades at their cutting edges including U-shaped resilient members arranged on opposite sides of the longitudinal center of the razor, each of said spacing members including inner and outer legs, the inner leg being disposed between the blades and having a corrugated form.

5. A safety razor comprising a guard, a clamping plate, means for adjusting the guard and clamping plate toward and away from each other, a pair of super-imposed blades arranged and clamped between said guard and plate, means for spacing the blades including a pair of substantially U-shaped resilient members arranged on opposite sides of the longitudinal center of the razor, each of said members including inner and outer legs, the inner leg being disposed between the blades, and means on the razor for engaging the other leg for holding the same against lateral shifting movement.

ETTA S. MARTIN.
